Term of patent 14 years

(Cl. D26—13)

Figure 1 is a perspective view of the combined electric unit and housing therefor or similar article, the opposite side being substantially a mirror image thereof, showing the electric unit disassociated from the housing, and showing our new design with the handle in unlocked position:

Figure 2 is a front elevational view of our invention with the handle in locked position; and,

Figure 3 is a rear elevational view.

Portions of the figures in the drawing are diagonally lined to indicate transparency

The pointers and dial markings in Fig. 2 have been omitted from Fig. 1 for convenience in illustration.

We claim:

The ornamental design for a combined electric unit and housing therefor or similar article, substantially as shown and described.
